UNITED STATES PATENT OFFICE.

THOMAS W. F. SMITEN, OF BROOKLYN, NEW YORK.

PEN AND PENCIL HOLDER.

SPECIFICATION forming part of Letters Patent No. 339,817, dated April 13, 1886.

Application filed August 19, 1885. Serial No. 174,797. (No model.)

To all whom it may concern:

Be it known that I, THOMAS W. F. SMITEN, of Brooklyn, in the county of Kings and State of New York, have invented a new and useful 5 Improvement in Pen and Pencil Holders, of which the following is a specification.

My invention relates to that class of devices which have provision for the attachment to them of two or more pen or pencil holders, 10 and which form a connection between such two or more holders and the stick or handle by which the implement is held when in use. In such devices two or more pencils or pens may be employed and used with one hand to 15 produce in ruling or writing two or more separate lines, or to produce lines which may be single in some parts and double in other parts. By employing pencils of different colors or pens dipped in different-colored inks, very 20 beautiful and pleasing effects may be produced.

The object of my invention is to provide a device or connection between the pencil or pen holders and the handle on which the 25 holders will be supported side by side, and which is so constructed that when pressure is applied through the handle the pencils or pens will be caused to spread laterally or move apart to produce separate lines and to vary 30 the distance between the lines produced by them, while when pressure is removed from the handle the pencils or pens will move inward or nearer together, so as to produce single lines, if desired.

35 The invention consists, essentially, in the combination, with two pen or pencil holders and a handle, of a connection between the holders and handle, comprising arms one or both of which are elastic or yielding, and 40 which are arranged side by side, and which, by pressure applied through the handle, will spread laterally in order to vary the distance between their attached holders. I also secure the pen or pencil holders upon the elastic 45 arms of the connection, so that said holders may be adjusted nearer to or farther from each other before the device is used, and by which construction provision is afforded not only for the spreading of the pens or pencils 50 automatically while in use, but for setting them at a definite distance apart before use. I also employ with the connection a cam,

which, by pressure applied through the handle, will be forced downward or introduced between the elastic arms in order to spread 55 them and their attached pen or pencil holders positively.

The two features of construction above described are included in my invention.

In the accompanying drawings, Figure 1 is 60 a plan of a device embodying my invention, showing two pens fixed in holders which are adjustable laterally toward and from each other upon the elastic arms of the connection. Fig. 2 is an end view of the connection and 65 pen-holders which are shown in Fig. 1. Fig. 3 is a sectional side view upon the plane of the dotted line x x , Fig. 1, showing the construction of the pen-holder, which is adjustable upon the elastic arm of the connection. 70 Fig. 4 represents a plan illustrating a modification of my invention, and Fig. 5 is an end view of the connection shown between the pen-holders and handle in Fig. 4.

Similar letters of reference designate corresponding parts in all the figures. 75

Referring first to Figs. 1, 2, and 3, a a designate two pens of ordinary form, which are fitted in holders b . The holders are made in the form of sockets, which conform more or less approximately to the transverse section of the pen, and which are constructed with elastic tongues b' , which lie upon the under side of the pens when inserted in the holders and form self-feeders for inking. The elastic 85 connection between the pen-holders b and the handle or stick A comprises a cylindric socket, c , into which the handle or stick is inserted, a downwardly bent or turned shank, d , (best shown in Fig. 3,) and elastic arms e , which 90 are arranged side by side and extend forward and then outward from the shank d . These elastic arms e are constructed with upwardly-projecting ears or wings e' , which are best shown in Figs. 2 and 3, and the stick or handle A may be inserted a sufficient distance through the cylindric socket c to come between these ears or wings e' ; hence it will be seen that when pressure is applied through the stick or handle A its inner projecting end will, 95 100 be forced downward between the ears or wings e' , and by such action will spread the ears or wings e' , and elastic arms e , from which they project. The elastic arms e carry the pen-

holders *b*, and, as represented, the pen-holders have formed in them mortises *b*², through which the elastic arms *e* are inserted, as best shown in Figs. 1 and 2. This construction and 5 method of attaching the pen-holders to the arms provides for sliding the pen-holders laterally upon the arms toward and from each other, so that the pens *a* may be set at definite distances apart.

It will be seen that when the elastic arms *e* are forced apart or spread laterally by the cam-like action of the handle or stick the pen-holders *b*, being attached to these arms, will likewise be spread laterally, and when 15 the stick or handle is relieved of pressure the arms *e* and their attached pen-holders will return laterally toward each other or nearer together by reason of the elasticity of the arms *e*.

20 The connection between the pen-holders *b* and the handle or stick A (shown in Figs. 4 and 5) is very similar to that above described, except that the elastic arms *e* are provided with cylindric sockets or slides *e*², in which 25 are inserted the cylindric or barrel-like pen-holders *b*. In this case, however, instead of utilizing the end of the handle or stick A as a cam to force the elastic arms *e* apart laterally, I have represented the cylindric stick-socket *c* 30 as continued forward sufficiently far to lie between the ears or wings *e*, and to serve as a cam for spreading them apart. In this case the sockets *e*² upon the end of the arms *e* are formed in the same piece or rigidly connected 35 with the arms *e*, and hence no provision is afforded for the adjustment of the pen-holders toward and from each other; but said holders and their pens are caused to move toward and 40 from each other only by the elasticity and flexibility of the arms *e*, and automatically.

It will be seen that by adjusting the pens *a* lengthwise in their holders their points may be brought nearer to or farther from each other, because the pen-holders and pens are arranged 45 so that they converge toward the points of the pens. The holders may even be adjusted so that the points of the pens or pencils may come so close together in their normal condition as to combine to form a single line. Then 50 by applying a varied pressure they may be made to diverge at various distances, to form lines which in places are single and in other places double, and at varying distances apart.

If my improved device is to be employed 55 for holding pencils, the pencils may be readily inserted into the sockets *e*² of the device represented in Figs. 4 and 5, in lieu of the barrel-like pen-holders *b*.

It is obvious that, instead of making both the arms *e* elastic or yielding, one of them 60 might be comparatively stiff and the other made sufficiently flexible to obtain the desired degree of separation by pressure applied through the handle.

In my application for Letters Patent, Serial 65 No. 174,529, filed August 17, 1885, I have shown and described a double or multiple pointed pen comprising a head or stock for insertion in an ordinary pen-holder and elastic shanks extending therefrom and provided at 70 their ends with converging pen-tips. I do not desire to include such a construction in my present invention, which consists in a device or connection whereby two pens of ordinary form may be connected with one holder or 75 stick.

What I claim as my invention, and desire to secure by Letters Patent, is—

1. The combination, with two pen or pencil holders and a handle, of a connection between the said holders and the handle, comprising arms one or both of which are elastic or yielding, and which are arranged side by side, whereby pressure applied through the handle will cause the holders to spread or separate laterally, and whereby the holders will contract or be brought nearer together when the handle is relieved of pressure, substantially as herein described.

2. The combination, with two pen or pencil holders and a handle, of a connection between the holders and handle, comprising arms one or both of which are elastic or yielding, and which are arranged side by side, and on which the holders are secured and capable of 95 lateral adjustment toward and from each other, whereby pressure applied through the handle will cause the arms and holders to spread or separate laterally, and whereby the arms and holders will contract or be brought nearer together when the handle is relieved of pressure, substantially as herein described.

3. The combination, with two pen or pencil holders and a handle, of a connection between the holders and handle, comprising arms 105 one or both of which are elastic or yielding, and which are arranged side by side, and to which the holders are attached, and a cam which, by pressure applied through the handle, is introduced between the arms and made 110 to spread them and their attached holders, substantially as herein described.
